UNITED STATES PATENT OFFICE.

WILLIAM J. BAUER, OF NEW YORK, N. Y., ASSIGNOR TO FOLTITE CHAIR CORPORATION, OF NEW YORK, N. Y., A CORPORATION OF NEW YORK.

COLLAPSIBLE CHAIR.

Application filed August 18, 1925. Serial No. 50,893.

The invention relates to chairs, more particularly of the folding or collapsible type designed generally to be stored away when not in use. It has for its object to provide 5 a chair of this character which while comparatively light shall be sufficiently rigid and of such substantial construction as to support comparatively heavy loads. The invention has for a further object to so construct the novel chair that the same shall 10 occupy but a minimum space whereby storage of the same may readily be accomplished when the chair is not desired for use. A still further object of the invention consists 15 in a construction which will admit of convenient collapse as well as setting up of the chair for use, the same being possible by the use of one hand only, as by inserting the same into a suitable hand hole provided in 20 the chair.

The nature of the invention, however, will best be understood when described in connection with the accompanying drawings, in which—

25 Fig. 1 is a side elevation of the novel chair in extended position and ready for use.

Fig. 2 is a front elevation, and Fig. 3 is a plan thereof.

Fig. 4 is a side elevation of the chair in 30 collapsed condition.

Referring to the drawings, the chair is shown as constructed essentially of a pair of front legs 10 and a pair of rear legs 11 hinged intermediate their ends about a rod 35 12, a seat 13 and a back 14. The lower portions of the rear legs are slightly longer than the corresponding portions of the front legs. A pair of arms 15, moreover, pivotally connect the seat and back at the respective sides 40 thereof; each of said arms being offset for a portion of its length to strengthen the chair against lateral play. A seat supporting rod 16, also, extends between the legs and is carried thereby beneath the seat 13 to support the latter, while bracing rods 17 45 and 18 are mounted between the rear legs and a similar rod 19 between the front legs. The upper ends of the two rear legs 11 are pivotally connected to the forward portion 50 of seat 13 while the upper ends of the front legs 10 or rather extensions thereof are pivotally secured to the back 14, said extension portions being located outside of the arms 15. The said arms, moreover, are provided 55 along the lower edge and between the ends

with hooks or stop members 20 which are designed to engage with the seat supporting rod 16 and limit thereby the forward movement of the seat 13.

The seat 13 as well as the back 14 may 60 be provided with suitable cushion members 21 and 22 respectively; and the frames forming said seat and back members may be made identical, thereby requiring but one die in the manufacture of the same. At the back 65 of the seat member, moreover, as well as at the top of the back member there are provided respective hand holes 23 and 24, the former being for use in grasping the seat in collapsing and setting up the same as hereinafter set forth; while the latter is for convenience in moving the chair about. 70

It will be noted that there is no continuous frame member from the bottom to top of chair as is the usual practice in connection with the construction of camp chairs and the like; but the construction herein set forth is such that the chair may be readily collapsed merely by grasping the same at the hand hole 23 and then bodily lifting the 80 chair with a slight upward turn. This will cause the hooks 20 to become disengaged from the seat supporting rod 16 and will cause the back 14 to fall over on the seat in moving about the pivot points 25, said back hinging also about the outer ends of arms 15 while at the same time the legs 10 and 11 close in about the rod 12. The chair then assumes the form shown in Fig. 4 with all parts substantially within the width of the 85 side of front legs 10 and with back 14 inverted over seat 13 as shown, which has moved upwardly about the top of the rear legs 11. The hand hole 23 is then also uppermost, and affords a convenient means for carrying the chair about while collapsed. In this collapsed condition, the seat occupies but a comparatively small space and is substantially flat so that there is no loss of 90 space in storing one chair upon the other. 95

In setting up the chair again, it is necessary merely to grasp the back portion at the hand hole 23 and guide the collapsed chair to bring the rear legs (which are slightly longer than the front legs, as aforesaid) into 105 contact with a floor, whereby with a slight downward pressure thereon the parts will fall into position until the movement is stopped by contact of the rod 16 with the hooks 20, the chair then assuming the pos- 110

tion shown in Fig. 1 and in which the upper or extension portion of the forward legs 10 provide sides or arms for the chair.

I claim:—

5. 1. A collapsible chair, comprising a rear pair of legs, a front pair of legs pivoted thereto between the ends thereof and extending above the upper end of said rear pair of legs, a seat member pivoted to the 10 upper end of the rear pair of legs, a back member pivoted to the upper end of the front pair of legs and beyond the bottom edge of which back member the rear of the seat member projects, a rod extending beneath the seat member and connecting the front pair of legs, and arms between the seat and back member providing a hinged connection therebetween, said arms having means extending therefrom for engaging the 15 said rod.
2. A collapsible chair, comprising a rear pair of legs, a front pair of legs pivoted thereto between the ends thereof and extending above the upper end of said rear 20 pair of legs, a seat member pivoted to the upper end of the rear pair of legs, a back member pivoted to the upper end of the front pair of legs, the seat member having a handle at the rear projecting beyond the 25 bottom edge of the back and whereby the chair may be grasped for collapsing and also for setting in position for use, a rod extending beneath the seat member and connecting said front pair of legs, and arms between the seat and back member providing a hinged connection therebetween, said arms having means extending therefrom for engaging the 30 said rod.
3. A collapsible chair, comprising a rear pair of legs, a front pair of legs pivoted thereto between the ends thereof and extending above the upper end of said rear pair of legs, a seat member pivoted to the upper end of the rear pair of legs, a back 35 member pivoted intermediate its length to the upper termination of the front pair of legs, the seat member having a handle portion at the rear projecting beyond the bottom edge of the back and whereby the chair may be grasped for collapsing and also for setting in position for use, a rod extending beneath the seat member and connecting the front pair of legs, means affording a hinged connection between the seat and back members and having means extending therefrom for engaging said rod.
4. A collapsible chair, comprising a rear pair of legs, a front pair of legs pivoted thereto between the ends thereof and extending above the upper end of said rear pair of legs, a seat member pivoted to the upper end of the rear pair of legs, a back member pivoted to the upper end of the front pair of legs and beyond the bottom edge of which back member the rear of the 40 45 50 55 60 65 70 75 80 85 90 95 100 105 110 115 120 125
- seat member projects, a rod extending beneath the seat member and connecting the front pair of legs, and arms between the seat and back member providing a hinged connection therebetween, and means associated with the chair seat for engaging the said rod.
5. A collapsible chair, comprising a rear pair of legs, a front pair of legs pivoted thereto between the ends thereof and extending above the upper end of said rear pair of legs, a seat member pivoted to the upper end of the rear pair of legs, a back member pivoted to the upper end of the front pair of legs, the seat member having a handle at the rear projecting beyond the bottom edge of the back and whereby the chair may be grasped for collapsing and also for setting in position for use, a rod extending beneath the seat member and connecting said front pair of legs, and arms between the seat and back member providing a hinged connection therebetween, and means associated with the chair seat for engaging the said rod.
6. In a folding chair comprising a pair of spaced rear legs, a front leg pivotally mounted to each of the rear legs and extending beyond the respective upper extremities of the last named legs, said leg structure being interconnected by rung means adapted to allow of folding the complementary members into closed or aligned position and of unfolding the same into open or crossed position, stop means serving to limit the unfolding of said leg members, a back member pivotally mounted between said pair of front leg extensions, a seat member pivotally mounted between the upper ends of the pair of rear legs and projecting rearwardly beyond the lower end of the back, supplemental support means associated with the front legs serving to uphold the unfolded seat relative to said seat pivots, and hinged means disposed between said back and seat members adapted to cooperate with the said members while unfolding the chair to guide the rearward portion of the seat underneath the back member, whereby the former projects beyond the latter and constitutes a seat manipulating element for chair folding purposes.
7. In a folding chair comprising a pair of spaced rear legs, a front leg pivotally mounted to each of the rear legs and extending beyond the respective upper extremities of the last named legs, said leg structure being interconnected by rung means adapted to allow of folding the complementary members into closed or aligned position and of unfolding the same into open or crossed position, stop means serving to limit the unfolding of said leg members, a back member pivotally mounted between said pair of front leg extensions, a seat member pivotally

mounted between the upper ends of the pair of rear legs and projecting rearwardly beyond the lower end of the back, supplemental support means associated with the front legs 5 serving to uphold unfolded seat relative to said seat pivots, and hinged means disposed between said back and seat members adapted to cooperate with the said members while unfolding the chair to guide the rearward 10 portion of the seat underneath the back member whereby the former projects beyond the latter and constitutes a seat manipulating element for chair folding purposes which by the raising thereof serves to swing the 15 unfolded back member into a reversed position with respect to the seat member, the seat and back members in folded chair position being made to assume substantial alignment with the folded leg members 20 whereupon said manipulating seat portion projects somewhat beyond the adjacent back member to also serve for chair unfolding purposes.

8. In a folding chair comprising a pair 25 of spaced rear legs, a front leg pivoted to each of the rear legs and extending beyond the respective upper extremities of the last named legs, said leg structures being interconnected by rung means adapted to allow

of folding said complementary members into 30 closed or aligned position and of unfolding the same into open or cross position, stop means serving to limit the unfolding of said members, a back member pivotally mounted between said pair of front leg extensions, a 35 seat member pivotally mounted between the upper ends of the pair of rear legs which pivots are adjoined to the front portion of the unfolded seat, supplemental support means associated with the front legs serving 40 to uphold the rear portion of the unfolded seat relative to said seat pivots, and hinged means disposed between said back and seat members adapted to cooperate with said members while unfolding the chair to guide 45 the rearward portion of the seat into engagement with said support means and adapted while closing the chair to swing the back member about its front leg extension pivots for reversibly folding the back member upon 50 the seat member and bring them into substantial alignment with the closed leg members, the outermost seat element being disposed to project beyond said adjacent back member to constitute an unobstructed manipulating means for chair opening purposes.

In testimony whereof I affix my signature.
WILLIAM J. BAUER.
